UNITED STATES PATENT OFFICE.

SAMUEL RAWSON, OF PEORIA, ILLINOIS.

WAGON-JACK.

SPECIFICATION forming part of Letters Patent No. 242,155, dated May 31, 1881.

Application filed April 20, 1881. (No model.)

To all whom it may concern:

Be it known that I, SAMUEL RAWSON, of Peoria, in the county of Peoria, in the State of Illinois, have invented an Improved Wagon-Jack; and I do hereby declare that the following is a full, clear, and exact description thereof, reference being had to the annexed drawings, making a part of this specification, in which like letters of reference refer to like parts, and in which—

Figure 1 represents side elevation, and Fig. 2 end elevation, of two wagon-jacks coupled together.

The lever A, pivoted at P, terminates at one end in the hand-piece B and at the other end in the concave axle-holder C. This lever A is supported by the double standard E, and its other end, B, kept from flying up from the weight of the wagon on the end C by means of the pin P', placed in one of the holes S' of the upright standard D, between the two parts of which the lever A moves. The upright D is fastened to the base F by the bolt L', and is kept in place by the pin or bolt P³ and the brace G'. By removing the pin or bolt P³ the upright D can be folded down against the base F. In the same way the upright E is secured to the base F by the bolt L, and held up by the brace G and pin or bolt P². To make this upright E perpendicular in case the base F rests on sloping ground, the pin P² can be removed, the upright E moved to a correct position, and the pin P² put back through the new hole S³ in the brace G. By removing the pin P² the upright E can also be folded down against the base F.

To adapt this wagon-jack to wagons of different heights, the pin P can be removed, the lever A changed to the suitable height, and the pin P put in at the new hole S of the upright E. The lever A can be pivoted at dif-

ferent holes, S², in it, when desired to adapt it to wagons of greater or less weight.

If it is wished to lift up both wheels at one end of a wagon at the same time, two wagon-jacks are fastened together by means of the notched bar H and bolts R R.

This wagon-jack can also be used for a carpenter's bench and vise—for a bench by pinning the lever A up horizontal, or for vise by means of the concave curve C'. The handle B can be raised, a piece of wood placed between the upright E and the concave part C' of the lever, the handle B pressed down till the piece of wood is firmly held, and the pin P' put in the proper hole S' to hold it.

What I claim as my invention, and for which I desire Letters Patent, is as follows, to wit:

1. In wagon-jacks, the lever A, with handle B, concave axle-holder C, concave face C', and holes S², in combination with the upright E, with its holes S, pin P, base F, bolt L, brace G, with holes S', pin or bolt P², also upright D, with holes S', pin P', brace G', with holes S³, pin or bolt P³, and bolt L', substantially as and for the purpose specified.

2. In wagon-jacks, the lever A, upright E, brace G, and base F, in combination with the notched connecting-bar H and bolts R R, substantially as and for the purpose specified.

3. In wagon-jacks, the lever A, provided with holes S², in combination with upright E, provided with holes S, the pin P, and base F, as set forth.

In testimony that I claim the foregoing invention I have hereunto set my hand this 16th day of April, 1881.

SAMUEL RAWSON.
